US00D973837S

(12) **United States Design Patent** (10) **Patent No.:** **US D973,837 S**
(45) **Date of Patent:** **** Dec. 27, 2022**

(54) **FILTER UNIT**

(71) Applicant: **Qingdao Ecopure Filter Co., Ltd,**
Qingdao (CN)

(72) Inventor: **Zhibin Zou**, Qingdao (CN)

(**) Term: **15 Years**

(21) Appl. No.: **29/681,136**

(22) Filed: **Feb. 22, 2019**

(51) **LOC (13) Cl.** **23-01**

(52) **U.S. Cl.**

USPC **D23/209**

(58) **Field of Classification Search**

(57) **CLAIM**

The ornamental design for a filter unit, as shown and described.

DESCRIPTION

FIG. 1 is a front elevational view thereof of a filter unit showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a perspective view thereof.

The broken lines in the drawing depict portions of the filter unit that form no part of the claimed design.

1 Claim, 7 Drawing Sheets
